UNITED STATES PATENT OFFICE.

WILLIAM A. MACK, OF CLEVELAND, OHIO, ASSIGNOR TO THE STANDARD SEWING MACHINE COMPANY, OF CLEVELAND, OHIO, A CORPORATION OF OHIO.

SEWING-MACHINE.

1,063,987.

Specification of Letters Patent. Patented June 10, 1913.

Application filed August 21, 1906. Serial No. 331,428.

To all whom it may concern:

Be it known that I, WILLIAM A. MACK, citizen of the United States, and resident of Cleveland, in the county of Cuyahoga and State of Ohio, have invented certain new and useful Improvements in Sewing Machines, of which the following is a specification.

This invention relates to stitch-forming mechanism adapted for use in either one-needle or two-needle lock-stitch sewing machines, but more especially designed for use in two-needle machines and being so illustrated herein.

The invention includes a rotative needle-thread looper fixedly attached to its actuating shaft and comprising a looper-arm preferably formed in the arc of a circle corresponding to the circular path of movement of the looper and having at one end thereof a reversely extended underhanging loop-seizing hook which is operative to take the thread-loop thrown out by the needle, carry it partially around a correlated bobbin-case to a point beyond the vertical center of the same, and then cast it off to be drawn up by the take-up into interlocking engagement with the bobbin-thread to complete the stitch in the usual manner; the said passage of the thread-loop about the bobbin-case as effected by the looper being in a path within the outer radius of movement of the looper by reason of the position of the loop-seizing hook underhanging its carrying arm and thereby assuring the passage of the thread-loop about the bobbin-case with a minimum length of thread drawn from the spool or other supply.

The invention also includes the combination with the looper of a guard arm so formed and positioned relative to its co-operating parts as to be capable of performing three functions including, first, pulling off sufficient thread from the bobbin to form with the needle-thread the successive lock-stitches; secondly, holding the bobbin-thread safely to one side the path of the rotative looper hook to avoid accidental catching of the bobbin-thread by said hook; and thirdly, causing the thread-loop thrown out by the needle being formed at that side of the needle next the path of movement of the looper hook to be positively seized by the latter.

The invention also includes novel features of construction of the bobbin-case holder whereby the holder is adapted to permit of quick and convenient insertion or removal of the bobbin-case and without interference with or by the looper or the guard element carried therewith.

These several features of invention, and others to be hereinafter referred to in the detailed description of the invention which follows, are applicable to either a one-needle or two-needle sewing machine, the same when applied to a two-needle machine as herein illustrated being duplicated and positioned for co-operation with the two needles. Certain features of the invention forming the subject-matter of this application, however, are particularly adapted to a two-needle machine and will be so described and claimed herein.

Referring now to the accompanying drawings forming part of this specification, Figure 1 is a longitudinal sectional elevation of such parts of a two-needle sewing machine as are necessary to illustrate the invention, with the needles just entering the work and with the looper-carried guards just engaging the bobbin-threads preparatory to pulling them from the bobbins for the formation of the next lock-stitch and also moving them laterally toward each other away from the path of movement of the looper hooks. Fig. 2 is a similar sectional elevation showing the looper devices turned forward from the positions of Fig. 1, to about their limit of forward oscillation, and showing how the guards have drawn the bobbin-threads laterally clear of the paths of the looper hooks while at the same time engaging the needle-threads at one side of the needles to compel their subsequently formed loops to project laterally into the paths of the looper hooks. Fig. 3 is a similar sectional elevation showing the first part of the reverse or rearward oscillatory movement of the loopers with their hooks just entering the needle-thread loops. Fig. 4 is a reverse or rear sectional elevation of the same mechanism showing the needle-thread loops being carried around by farther rearward oscillation of the loopers, and also shows how the opened thread loops are engaged by relatively stationary wedge-shaped parts of the bobbin-cases. Fig. 5 is a front sectional

view, similar to Figs. 1, 2 and 3, with one of the loopers partly broken away, and illustrates the limit of rearward oscillation of the loopers with the underhanging looper hooks casting off the thread-loops which are now being drawn up by the take-up mechanism to complete the stitches. Figs. 6, 7 and 8, are respectively top, bottom and side views of the duplex looper shown in the preceding figures of the drawings. Fig. 9 is a detail end view illustrating the finger operative devices controlling the movable walls of the bobbin-case holder. Fig. 10 is a longitudinal section of the bobbin-case holder on the line *a*—*a* in Fig. 9, and illustrates by dotted lines the method of releasing one of the two bobbin-cases. Fig. 11 is a section on the line *b*—*b* in Fig. 9 looking in a direction toward the arrow points, and indicates by dotted lines the mode of releasing the other bobbin-case. Fig. 12 is an enlarged side view of one of the bobbin-cases and contained bobbin, with the bobbin-latch closed. Fig. 13 is a similar side view showing the bobbin-latch open. Fig. 14 is a cross-section taken on the line *c*—*c* in Fig. 12. Fig. 15 is a plan view of a modified form of looper; and Fig. 16 is a side view of this modification.

First referring more particularly to Figs. 1 to 8 inclusive of the drawings, the numeral 1 indicates a horizontal rock-shaft journaled in suitable bearings at the under side of the sewing-machine bed-plate 2, and the numeral 3 indicates generally the duplex looper device attached to the front end of said rock-shaft to be supported and actuated thereby. The looper 3 comprises a shank portion 4 extending radially from the shaft 1, to which it is held by a set-screw 5, and having at its outer end a laterally extended plate 7 parallel with the axis of the shaft, which plate, in the duplex form of looper herein shown, is provided with two arms 8—8 extending forwardly therefrom in the shape of a circle corresponding to the circular path of movement of the looper and each having at its forward end the reversely extended underhanging loop-seizing hook 9. These hooks are preferably formed with their points 10 projecting slightly inwardly beyond the plane of the inner edges of the looper arms 8—8, as best shown in Figs. 6 and 7, in order to move in a path adjacent to the path of movement of the vertically reciprocating needles 12—12, which latter move through an opening 13 between the looper arms 8—8 when descending to throw out the thread-loops to be seized by the looper hooks, and at a point opposite or immediately above the hook points 10 the looper arms 8—8 are preferably formed with an upwardly curved portion 14 to provide ample clearance space for the thread-loops thrown out by the needles, as shown in Fig. 3. From their points 10 the looper

hooks gradually widen to considerable width at their heels or rear ends in order to open or spread apart widely the sides of the seized thread-loops preparatory to carrying them around the bobbin-case, in a manner to be hereinafter referred to. The triple-function guard arms carried by the looper and indicated at 15—15 are shown as projecting from a fastening plate 15' secured to the looper plate 7 and as being arranged in a plane between the looper arms 8—8 with a space between their outer edges and the adjacent looper arms for the passage of the needles and with a central bobbin-thread receiving space or slot 17 between the same. These guard arms, like the looper arms, are also preferably curved to substantially conform to the circular path of movement of the looper and at their outer ends project forwardly beyond the ends of the looper arms and diverge laterally outward from each other in position to engage the bobbin-threads extending between the bobbins and the work; the inner or adjacent edges of the diverging ends of the guard arms forming cam surfaces 18—18 for acting on the bobbin threads in manner assuring the pulling off of sufficient lengths of thread required in the formation of the successive lock stitches, and also the moving of said threads laterally away from the paths of the looper hooks, while the outer edges 19 of the guard arms at their rear ends are so positioned as to coöperate with the needles in a manner to cause the forming thread loops to be thrown out by the needles at that side thereof next the looper hooks and so assure the positive seizing of the loops by the hooks, as hereinafter more fully explained.

As will be seen, the following features are presented in connection with the particular structure of looper, disclosed herein: The edge of the hook facing the needle space has a major portion of its length in substantial radial alinement with the similar edge of the arm, thereby providing an over-hang for the hook which substantially covers all but the point of the hook and tends to eliminate liability of the hook picking up threads, (either loose, a bobbin-thread, or a part of the stitch thread) excepting the thread be practically projected under the arm, the exposure of the point of the hook to a straight thread being relatively small. Since the hook extends rearwardly in comparatively close proximity to the arm, and thereby decreases the liability of such picking up of threads, the arched portion (14) is provided opposite the point of the hook to increase the space between the arm and hook and affords a sufficient clearance to permit a proper projecting of the thread loop to bring it under the arm of the looper and thus insure the hook engaging the loop, this

clearance being, however, provided only in the immediate vicinity of the point of the hook, the remainder of the hook having the normal distance between the hook and arm; 5 by this latter construction the hook is not deflected at its point out of the normal path provided by the major portion of the remainder of the hook, the entire hook structure extending in substantially a single 10 curved line concentric with the axis of rotation of the looper. Furthermore, as more particularly shown in Fig. 8, the guard 15 is positioned in advance of the arm on the line of the needle path of movement during 15 the withdrawal movement of the needle, said guard thereby operating on the thread sufficiently in advance of the looper arm to cause the thread loop to be positively projected laterally under the arm, the edge of the arm 20 facing the needle space forming an abutment operating to prevent elongation of the loop in a direction corresponding to the direction of length of the needle, the thread loop being of a form to actually enter under the looper arm with a thread portion extending between the arm and the point of the hook.

The construction of the improved duplex bobbin-case holder will now be described 30 with more special reference to Figs. 1, 9, 10 and 11 of the drawings. In the outer end of the frame or bed-plate 2, and preferably in axial alignment with the looper shaft 1, is fitted a block or support 20 which, when 35 properly adjusted, is fixedly held in position by a set-screw 20' threaded into the frame. Near its edge this block 20 fixedly carries two inwardly projecting pins 21—21 on which are placed three disks or wall sec- 40 tions 22, 23, 24, the opposing faces of which have suitable projections 25 which engage peripheral portions of the bobbin-cases to 45 loosely support said cases in manner permitting the needle thread loops being readily passed around them. The two outside or 50 end disks 22, 24, are slidably mounted on the pins 21, while the central disk 23 is fixed upon the pins, thus permitting either outside disk 22, 24, to be moved on the pins relatively to the central disk 23 for permitting 55 insertion or removal of the bobbin-case therebetween. Any suitable means may be employed for so moving the outer or end disks 22, 24, relatively to the central disk 55 60 65 70 75 80 85 90 95 100 105 110 115 120 125 130

22 and their outer ends connected to an actuating device 27, and the means for operating the other disk 24 comprising a rod 29 also slidably mounted in the block 20 between the rods 26—26 with its inner end connected to the disk 24 and its outer end having operative engagement with an actuating device 30. As the disk 24 is movable in a direction inwardly or away from the block 20 to permit insertion or removal of a bobbin-case between it and the disk 23, its actuating device 30 is in the form of a push-plate for pressing inwardly against the engaging rod 29 to move the connected disk to the open dotted line position shown in Fig. 10 and which push-plate is shown as carried by a supporting and guiding plunger 31 slidably fitted in a central opening in the block 20. As the other disk 22 is movable in a direction toward the block 20 to permit insertion or removal of a bobbin-case between it and the disk 23, its actuating device 27 is in the form of a pull-lever for drawing the connected rods 26—26 outwardly to move the attached disk to the open dotted line position shown in Fig. 11, the said lever having a loose connection at one end with the headed ends 26' of the rods 26 and fulerunning loosely upon projections 32 on the face side of the block 20. The lever 27 is also preferably formed with an offset therein to project its lower or actuating end to a position at the front side of the block 20 convenient to be reached by the operator, and is further provided with a central slot or opening in its upper end to receive the push-device 30 and prevent turning of the same from its position for engagement with the rod 29. Spacing sleeves 33—33 located on the rod 29 between the central disk 23 and the movable outer disks 22, 24, serve to determine the normal closed positions of the latter disks, and as a simple and convenient means for movably holding said disks in such normal closed position I have located a coiled spring 34 on the rod 29 which expands between a head 35 on said rod and the disk 22, as most clearly shown in Fig. 10. This spring 34 also obviously operates to automatically return the disks 22, 24, to their closed positions after being moved to open or releasing positions by their described actuating devices.

A bobbin-case and bobbin are drawn to an enlarged scale in Figs. 12, 13 and 14 of the drawings. The bobbin-case comprises an annular rim 40 for peripherally inclosing a bobbin 41 and having at one side thereof an integral inwardly-turned bobbin-retaining flange 42 and at its opposite side a movable bobbin-retaining flange 43, the latter being carried by a latch 44 pivoted to the case rim at 45 whereby it may be moved from its bobbin retaining position, as shown in Fig. 13, to permit of

insertion or removal of a bobbin. The latch 44 is also formed with a reversely-inclined or wedge-shaped outer face 46 which operates to engage the sides of the thread loop 5 carried around the bobbin-case by the looper and guide the same to opposite sides of the bobbin-case for assuring interlocking engagement of the thread-loop with the bobbin-thread, in manner to be hereinafter further referred to. Located on the bobbin-case adjacent to the latch 44 and in position to be partially covered thereby is a screw-adjusted bobbin-thread tension spring 48 under which the bobbin-thread 49 is adapted to be passed through a slot 50 in the bobbin-case, and from which tension-spring the thread passes to the work through a guiding eye-piece 51 located on the bobbin-case adjacent to the end of said spring. A second eye-piece 52 on the bobbin-case provides a convenient form of stop for bearing against one of the bobbin-case-holder cross rods, as shown in Fig. 4, to hold the bobbin-case against rotary movement during the operation of the machine.

The modified form of looper shown in Figs. 15 and 16 of the drawings, is especially designed to permit two needles to work more closely together than is possible with the looper shown in the preceding views. This result is attained by making the two guard arms of narrow wires 52-53, which for the most part overlie each other and thereby permit the two adjacent needle-thread loop-seizing hooks 54-54 to be brought more closely together. This contraction in width space occupied by the hooks and guards obviously permits two needles working between the hooks and guards to be arranged closer to each other for making two more narrowly spaced rows of stitches.

The successive steps of the process of forming lock-stitches in the work by this improved mechanism will now be described with more special reference in Figs. 1 to 5 of the drawings. In Fig. 1 the needles 12 are shown just entering the work 55 with their threads 47, and the looper guard arms 50-55 are shown with their inner or cam surfaces just engaging the bobbin-threads 49 which extend between the bobbin-cases and the work. As the loopers are now turned forward toward the operator by the shaft 1, the two guard arms carried therewith, by drawing the engaged bobbin-threads toward each other and into the narrow slot therebetween, operate to pull sufficient lengths of bobbin-thread from the bobbins 60 for the formation of the succeeding lock-stitch, and also to carry the bobbin-threads laterally out of the paths of movement of the looper hooks 9. This forward movement of the loopers and guard arms continues until the descending needles have

reached their lowest limit of movement and the points of the looper hooks have reached a position in advance of the needles, as shown in Fig. 2, at which time also the outer edges 19 of the guard arms are in position 70 for engagement with the needle-thread at the adjacent side of the needles and the upwardly curved bends 14 of the looper arms are in position at the opposite side of the needles to provide ample clearance for the 75 presently to be formed thread-loops. From this position of the parts shown in Fig. 2, the needles begin to ascend and the loopers and guard-arms begin their rearward oscillatory movement, the ascending needles 80 operating to throw out thread loops in the usual manner to be seized by the looper hooks and the guard arm surfaces 19 operating to positively assure the formation or throwing out of said thread-loops at the 85 proper side of the needles to be entered by the looper hooks, as shown in Fig. 3. As the rearward movement of the loopers continue from the position shown in Fig. 3 with the looper hooks just seizing the needle 90 thread loops, the said hooks operate to draw the thread loops into the broad bights at their heel or rear ends and thereby open or spread apart the sides of the loops preparatory to carrying them in the continued 95 movement of the loopers into engagement with the wedge-shaped faces 46 of the bobbin-cases, as shown in Fig. 4, by which they are positively guided to the opposite side of the bobbin-cases. Further continuance 100 of the rearward oscillatory movement of the loopers from the position shown in Fig. 4 carries the thread loops beyond the vertical center of the bobbin-cases and casts off the same, as shown in Fig. 5, at which time 105 the take-up mechanism operating above the bed-plate draws up the cast-off loops into interlocking engagement with the bobbin-threads and completes the formation of the lock-stitches in the usual manner. The modified looper shown in Figs. 15 and 16 of the drawings operates in substantially similar manner as regards the pull-off of bobbin-threads from the bobbin, the moving of these threads laterally out of the paths of the loop seizing hooks, and the guiding of the loops laterally outward at the proper side of the needles to assure positive engagement of the needle thread loops by the looper hooks during formation of two more closely 115 arranged parallel rows of stitches in the work.

Newly filled bobbins may be substituted for empty ones in the following manner: Finger pressure on the actuating end of the 120 lever 27 will operate the lever to draw upon the rods 26 and move the bobbin holding disk 22 outward on the guide pins 21, and against the tension of the spring 34, as indicated by dotted lines in Fig. 11 of the 125

drawings, thus freeing the supported bobbin-case and allowing the same or another case containing a filled bobbin to be quickly and easily inserted in position by the operator. When the lever 27 is released the spring 34 at once slides the disk 22 inward again to hold the inserted bobbin-case between the two disks 22, 23. The push-device 30 will next be pushed inward to press the rod 29 rearward against the tension of the spring 34, thereby moving the inner disk 24 inward on the guide pins 21, as indicated by the dotted lines in Fig. 10 of the drawings, to allow removal of the inner bobbin-case with its empty bobbin and the insertion of the same or another case with a filled bobbin. This being done and the plunger released, the spring 34 expands and restores the disk 24 to normal position to hold the inserted bobbin-case between the disks 23, 24.

As before intimated, the herein described loopers with their underhanging needle-thread loop-seizing hooks and the triple-function thread guards may operate substantially as set if the loopers be arranged to oscillate through a complete rotation instead of having the preferred oscillatory movement described. Furthermore, the machine may be operated to sew either one or two rows of stitching by the threading of either one or both needles, it being understood that each coöperating needle and looper operates in the formation of a stitch independently of the other coöperating needle and looper.

What I claim is:

1. In a sewing machine, a rotative looper having a curved arm extending in the direction of movement of the looper, said arm having an intermediate portion arched outwardly from the curved plane of the arm and adapted for registration with a needle upon its initial forward movement to form a thread loop whereby the loop is bulged beneath the arched portion, said arm further having an underlying loop-seizing hook the bill of which is located immediately beneath said arched portion and adapted to enter the thread loop.

2. In a sewing machine, a rotative looper having an arm curved in the direction of movement of the looper and provided with an intermediate portion arched upwardly from the curved plane of the arm and adapted for location at one side of a needle as it moves upwardly to loop a thread, said arm also having an underlying loop-seizing hook the bill of which terminates immediately beneath said arched portion whereby to enter the thread loop, and a guard arm lying in the curved plane of the looper arm and being spaced therefrom to receive the end of the needle between the arms, said guard arm having the portion of its edge adjacent the

needle during the upward movement of the needle lying in a single vertical plane and adapted to bear against the needle whereby to direct said thread loop beneath the arched portion of the looper arm and into the path of said loop-seizing hook. 70

3. In a sewing machine, the combination with a reciprocating thread looping needle, of a rotative looper having an arm curved in the direction of movement of the looper and provided with an underlying loop-seizing hook, a guard arm located in the plane of the looper arm and being spaced slightly therefrom to accommodate the end of the needle between the arms, said looper arm having a portion thereof arched outwardly from the curved plane of the looper arm and adapted to register with the needle upon its initial upward movement to form the thread loop, said guard arm engaging at its inner edge throughout a portion of its length against the inner side of the needle whereby to direct the thread loop outwardly beneath the arched portion of the looper arm, and into the path of said loop-seizing hook. 80

4. In a sewing machine, the combination with a reciprocating needle adapted to loop a thread, of a rotative looper having an arm, and a guard arm on the looper spaced from the looper arm to accommodate a needle between the arms, said looper arm having an outwardly bulged portion intermediate its ends adapted to register with the needle when the latter forms the thread loop, said guard arm engaging throughout a portion of its length against the inner side of the needle opposite to the bulged portion of the looper arm and adapted to direct the thread loop outwardly beneath the bulged portion of the looper arm, said looper arm further having a loop-seizing hook returned beneath the arm and terminating immediately beneath the bulged portion for engagement in the thread loop. 90

5. In a sewing machine, the combination with the needle and the bobbin, of a rotative looper having an arm carrying an underhanging loop-seizing hook and a guard, the latter being operative to project the loop-thread into position for engagement by the loop-seizing hook and to engage the bobbin-thread and pull it from the bobbin. 100

6. In a sewing machine, the combination with the needle and the bobbin, of a rotative looper having an arm carrying an underhanging loop-seizing hook and a guard, the latter being operative to project the loop-thread into position for engagement by the loop-seizing hook and to engage the bobbin-thread in advance of the looper hook and move it laterally from the path of the latter. 110

7. In a sewing machine, the combination with the needle and the bobbin, of a rotative looper having an arm carrying an underhanging loop-seizing hook and a guard, 120

- the latter being operative to project the loop-thread into position for engagement by the loop-seizing hook and to engage the bobbin-thread in advance of the looper hook and move it laterally from the path of the latter and also pull it from the bobbin.
8. In a sewing machine, the combination with the needle and the bobbin, of a rotative looper having an arm carrying an underhanging loop-seizing hook and a guard arranged to move at opposite sides the path of movement of the needle, the said guard having a cam surface operative to engage the bobbin-thread and move it laterally from the path of the loop-seizing hook and also pull it from the bobbin and serving to project the loop-thread under said arm and into position for engagement by the loop-seizing hook.
9. In a two-needle sewing machine, the combination with a pair of reciprocating needles adapted to form a pair of thread loops, a rotative looper having a pair of spaced arms adapted for movement against the outer sides of the needles and having registering outwardly bulged portions projecting from the plane of the looper arms and adapted to register with said needles when forming the thread loops, and a pair of guard arms carried by the looper and disposed between said looper arms and having their opposite edges throughout a portion of their lengths bearing against the inner sides of the needles and in registration with said bulged portions of the looper arms whereby to direct the thread loops outwardly beneath the bulged portions of the looper arms.
10. In a two-needle sewing machine, a rotative looper having two substantially parallel looper arms arranged with a needle space therebetween and each being provided with an underhanging loop-seizing hook, the points of which hooks extend laterally toward each other.
11. In a two-needle sewing machine, a rotative looper having two loop-seizing hooks and two guards, said guards being co-operative with the needles for projecting the thread loops thrown out by the needles into position for engagement by the loop-seizing hooks, and having diverging ends adapted to receive the bobbin threads between them.
12. In a two-needle sewing machine, a rotative looper having two loop-seizing hooks and two guards, the said guards being co-operative with the needles at that side of the same opposite the loop-seizing hooks, for projecting the thread loops thrown out by the needles into position for engagement by the loop-seizing hooks, and having diverging ends adapted to receive the bobbin threads between them.
13. In a two-needle sewing machine, a rotative looper having two looper arms each being provided with an underhanging loop-
- seizing hook substantially covered thereby and with an upwardly arched portion opposite the point of said hook providing a loop-clearance space, and two guards movable with the looper and being co-operative with the needles for projecting the thread loops thrown out thereby into position for engagement by the loop-seizing hooks.
14. In a two-needle sewing machine, a rotative looper having two substantially parallel looper arms arranged with a needle space therebetween and each being provided with an underhanging loop-seizing hook, and two guards carried by said looper in the space between the looper arms and being co-operative with the needles for projecting the thread loops thrown out by the needles into position for engagement by the loop-seizing hooks.
15. In a two-needle sewing machine, a rotative looper having two substantially parallel looper arms arranged with a needle space therebetween and being provided with an underhanging loop-seizing hook, and two guards carried by said looper in the space between the looper arms and being co-operative with the needles at that side thereof opposite the loop-seizing hooks for projecting the thread loops thrown out by the needles into position for engagement by the loop-seizing hooks.
16. In a two-needle sewing machine, a rotative looper having two substantially parallel looper arms arranged with a needle space therebetween and each being provided with an underhanging loop-seizing hook and with an upwardly arched portion opposite said hook providing a loop-clearance space, and two guards carried by the looper in the space between the looper arms and being co-operative with the needles for projecting the thread loops thrown out thereby into position for engagement by the loop-seizing hooks.
17. In a two-needle sewing machine, the combination with two bobbins, of a rotative looper having two looper arms arranged with a needle space therebetween and each being provided with an underhanging loop-seizing hook, and two guards carried by the looper in the space between the looper arms and being operative to engage the bobbin threads and pull them from the bobbins.
18. A duplex bobbin-case holder for sewing machines, comprising three disks or walls having means for holding two bobbin-cases between them, the two end disks being each movable toward and from the relatively fixed central disk.
19. A duplex bobbin-case holder for sewing machines, comprising three disks or walls having means for holding two bobbin-cases between them, the two end disks being each movable toward and from the relatively fixed central disk, and actuating devices op-

eratively connected with the end disks to move them.

20. A duplex bobbin-case holder for sewing machines, comprising a block or support on the machine frame, parallel pins sustained by said block, three disks or heads having means for holding two bobbin-cases between them and sustained on said pins, and means for moving the two end disks independently toward and from the relatively fixed central disk.

21. A duplex bobbin-case holder for sewing machines, comprising a block or support on the machine frame, parallel pins sustained by said block, three disks or heads having means for holding two bobbin-cases between them and sustained on said pins, spacing sleeves or means on one of the pins normally separating the three disks, and means for moving the two end disks independently toward and from the relatively fixed central disk.

22. A bobbin-case holder for two needle sewing machines, comprising a block or support held to the machine frame, guide pins fixed to said block, a rod movable endwise in the block, three bobbin-case holding disks or walls on said guide pins and rod, the central disk being fixed to the guide pins and the inner and outer disks being loose on said guide pins, and the inner disk being fixed to the endwise movable rod; pins fixed to the outer disk and being movable in the supporting block, spacing sleeves or means on the rod between the three disks, a spring normally expanding between the head of the rod and the outer disk, and means operative to independently move the inner disk supporting rod and the outer disk-carrying pins

for moving the inner and outer disks respectively.

23. A bobbin-case holder for two-needle sewing machines, comprising a block or support held to the machine frame, guide pins fixed to said block, a rod movable endwise in said block, three bobbin-case holding disks or heads on said guide pins and rod, the central disk being fixed to the guide pins and the inner and outer disks being loose on said guide pins, and the inner disk being fixed to the endwise movable rod; pins fixed to the outer disk and movable independently in the supporting block, spacing sleeves or means on the rod between the three disks, a spring normally expanding between the head of the rod and the outer disk, a lever fulcrumed on the block and connected with the outer disk-carrying-pins to move the outer disk, and a plunger fitted in the block and having a part engaging the inner disk-holding-rod to move the inner disk.

24. In a sewing machine, the combination with a looper having an underhanging loop-seizing hook, of a guard having an end to engage the bobbin thread, withdraw thread from the bobbin for the formation of the next stitch, and remove said thread from the path of the needle and the needle loop-seizing hook, said guard also having a part to compel the needle thread loop to be thrown into the path of the needle-seizing loop.

Signed at Cleveland, in the county of Cuyahoga and State of Ohio this 17th day of August A. D. 1906.

WILLIAM A. MACK.
